UNITED STATES PATENT OFFICE.

ADOLPH VESTER, OF NORTH ATTLEBOROUGH, MASSACHUSETTS.

BRACELET.

SPECIFICATION forming part of Letters Patent No. 237,344, dated February 1, 1881.

Application filed November 17, 1880. (No model.)

To all whom it may concern:

Be it known that ADOLPH VESTER, of North Attleborough, in the county of Bristol and State of Massachusetts, have invented a new and useful Improvement in Bracelets; and I do hereby declare that the following is a full, clear, and exact description of the same.

My invention relates to the class of bracelets; and it consists in an improved construction 10 of the hinge by which the two arms composing the bracelet are secured together, and by which construction the exterior of the bracelet presents a smooth unbroken surface, and no peak or head or other receptacle for the spring 15 is required.

In the drawings accompanying this specification, Figure 1 shows a section taken centrally through the bracelet, and Fig. 2 a view of the hinge.

20 In the drawings A A' represent the two arms or wings which compose the bracelet. They are constructed of tubing, curved to the required shape, and may be made of gold, silver, or any suitable metal or material.

25 To the part A, and fitting within the end of such part is a plate, 1, having ears 2 projecting outward. This plate may be soldered to the interior surface of the tube or attached in any other suitable manner.

30 A plate, 3, which may be formed either solid, or by bending a strip of metal to the required shape, is provided at one end with a projecting ear, 5, and a pin, 6, passes through the ears 2 and 5 and allows the plate 3 a free movement.

35 The plate thus has a free movement on the pin. The plate 3 extends into the tubular arm A' and allows such arm to form a close joint with the arm A. A spring, 7, is secured

to the other end of plate 3 and extends into the arm A' a whole or part of its length, and 40 is held at its other end by a pin passing through such arm or in any other suitable manner. It will thus be seen that the spring tends to keep the free arms of the bracelet together, while the hinge itself is totally concealed within the 45 tubular arms. This form makes a very neat and simple hinge-fastening, not liable to get out of order. The other ends of the bracelet may be provided with any suitable clasp or snap for holding them together.

Having thus described my invention, what I claim, is—

1. A bracelet composed of hollow sections A A', having a concealed joint, in combination with a spring contained within one of such 55 hollow sections, whereby the bracelet is made self-closing.

2. A hinge-joint for a bracelet, consisting of a plate hinged to one of the sections of the bracelet and extending into the adjoining hollow section, whereby such adjoining sections are permitted to make a close fit and present 60 an unbroken surface.

3. The described bracelet, consisting of the part A, the plate 3 hinged thereto, the spring 65 7 secured to such plate 3, and the tubular portion A', to which the other end of said spring 7 is secured, whereby the exterior surface of the bracelet is rendered smooth and unbroken.

In testimony whereof I have signed my name 70 to this specification in the presence of two subscribing witnesses.

ADOLPH VESTER.
